CLAIM

We claim, the ornamental design for a luminaire, as shown and described.

DESCRIPTION

FIG. 1 is a top perspective view of an embodiment of the invention;

FIG. 2 is a side view of the embodiment of FIG. 1, the luminaire being symmetric about a center axis;

FIG. 3 is a top view of the embodiment of FIG. 1; and,

FIG. 4 is a bottom view of the embodiment of FIG. 1.

The phantom lines shown in FIG. 1-4 are environmental and not part of the claimed design.

The surface treatment of the luminaire forms no part of the claimed design; a luminaire according to the claimed design may have any surface treatment.

The color of the luminaire forms no part of the claimed design; a luminaire according to the claimed design may be of any color or combination of colors.

References to “top”, “bottom” and “side” in the figure descriptions are not meant to require certain in-use orientation, a luminaire according to the claimed design may be used in any orientation.
